UNITED STATES PATENT OFFICE.

FRANK C. DE REAMER, OF SCHENECTADY, NEW YORK, ASSIGNOR TO GENERAL ELECTRIC COMPANY, A CORPORATION OF NEW YORK.

ROSETTE.

937,427.

Specification of Letters Patent. Patented Oct. 19, 1909.

Application filed July 3, 1908. Serial No. 441,730.

To all whom it may concern:

Be it known that I, FRANK C. DE REAMER, a citizen of the United States, residing at Schenectady, county of Schenectady, State 5 of New York, have invented certain new and useful Improvements in Rosettes, of which the following is a specification.

This invention relates to devices for effecting connections between the terminals of 10 electric circuits, and its object is to provide an improved rosette for ceilings or walls having concealed wiring and a contact-carrying cover or cap capable of separation by a direct pull.

15 The invention consists in certain details of construction hereinafter set forth and particularly pointed out in the claims.

In the accompanying drawing, Figure 1 is a side elevation, partly broken away, of 20 my improved rosette; Fig. 2 is a longitudinal section of the same on a plane substantially at right angles to Fig. 1; Fig. 3 is a bottom plan view of the base portion; Fig. 4 is a top plan view of the body portion, and Fig. 5 is a top plan view of the whole partly broken away.

The base 1, body 2 and cap 3 are made of insulating material, preferably molded porcelain. The rosette illustrated is circular in 30 cross section, but this particular shape is immaterial. The under face of the base is slightly recessed leaving along its edge a flange 4 within which the upper end of the body fits snugly. The body is secured to 35 the base by a central longitudinal screw bolt 5, having its head countersunk in the body, and its nut 6 countersunk in the base. Two flat terminal-plates 7 are secured by screws 8 to the under face of the base 1, adjacent 40 to the holes 9 through which the line wires 10 enter. Binding screws 11 in said plates fasten said wires thereto. To the upper surface of the body 2 are secured two flat contact plates 12 so located that when the body 45 and base are assembled and properly orientated by the interlocking notches 13 and lugs 14 the contact-plates and the terminal plates lie across and in contact with each other, as shown in Fig. 5. Clips 15 are 50 housed in deep recesses 16 entering the body 2 from below on each side of the screw 5,

and connecting screws 17 pass through the contact-plates into said clips. The cap 3 carries two fingers 18 forming the terminals of the work circuit leads 19 which pass down 55 through a central opening 20 in said cap. The fingers are arranged to enter the resilient clips when the cap is closed upon the lower end of the body. The clips exert a clamping hold upon the fingers sufficient to 60 support the cap and the leads, but a sharp pull on said cap or the leads will detach the cap and open the circuit.

The simplicity of construction, ease of 65 wiring, concealment and protection of conducting elements, and the neatness and symmetry of appearance combine to render this rosette a distinct advance in the art.

What I claim as new and desire to secure by Letters Patent of the United States, is: 70

1. A rosette comprising a base, a body and a cap, flat terminal-plates on the under side of the base, coöperating flat contact-plates on the upper end of the body, means for securing said base and said body together, 75 contacts connected to the contact plates of said body, and contacts on said cap adapted to detachably engage the contacts on said body.

2. A rosette comprising a base, a body having recesses entering from its lower end, and a cap, flat terminal-plates on the under side of the base, flat contact-plates on the upper end of the body, clips in said recesses connected with said contact-plates, and fingers on said cap adapted to enter said clips and be detachably held thereby.

3. A rosette comprising a base having a flange along its edge, a body adapted to fit inside said flange, a central fastening screw 90 passing through said body and base, flat co-operating plates on the adjacent surfaces of said base and body, clips carried by said body and in circuit with said plates, and a cap carrying fingers adapted to enter said 95 clips and be detachably held thereby.

In witness whereof, I have hereunto set my hand this 2nd day of July, 1908.

FRANK C. DE REAMER.
